Attorney.

UNITED STATES PATENT OFFICE

ELLA COX, OF MAGNOLIA, NORTH CAROLINA

INSERTABLE GRATE FOR BOX STOVES

Application filed April 24, 1928. Serial No. 272,523.

This invention relates to stoves, and especially to an insertable grate for box stoves.

The main object of this invention is to provide a well known type of wood-burning stove, known as a "box stove," with a grate 5 that can be passed into the door thereof and assembled therein, which is comparatively simple and cheap to manufacture, and which is very practical and useful in utilizing said 10 box stove for the burning of coal, lignite, chips, etc.

Other objects and important features are pointed out or implied in the following details of description in connection with the 15 accompanying drawings in which:

Figure 1 is a front view illustrating a body of a box stove having my grate therein, illustrated by dotted lines.

Figure 2 is a longitudinal vertical sectional 20 view taken in the line 2—2 of Figure 1.

Figure 3 is a vertical cross sectional view taken in the line 3—3 of Figure 2.

In these views, the stove legs and other parts are omitted, which have no direct connection with the grate and its relation to the 25 box stove.

Referring to these drawings in detail, in which similar reference numerals refer to similar parts in the several views, and in which 30 the stove body or box 4 has a doorway 5, flanges 6 at opposite sides of the doorway, a hinged door-closure 7, a draft-apron 8, a removable cover 9 for the latter, and an opening 10 through which coal and the like may 35 be introduced and which may be closed by means of the usual cover (not shown), the invention will now be described in detail as follows:

A horizontal grate member 11 is provided 40 with supporting flanges 12 at its opposite sides, so its main part is spaced above the floor of the box stove 4, and ashes may be drawn forward into the draft apron 8 and there removed with a shovel, as is usual. This 45 member 11 is provided with several openings

13 near the front end, but at a distance inward from the front end.

An upright grate member 14 has legs 15 the lower parts 16 of which are reduced so they can be passed through the openings 13 and fit loosely therein, while the upper parts 50 of these legs are too large to enter the openings 13, so their shoulders 17 rest on the top of the grate member 11. By the provision of this form of legs 15—16—17, spaces are provided at 18, directly over the grate member 55 11, and through these spaces 18, a poker can be thrust along the top of the member 11, under the coal or other fuel, so as to dislodge the same from its direct contact with the grate, to cause the ashes to fall through the grate, and thereby to permit a draft to pass up through the grate and through the fuel. Moreover, 60 because of the loose engagement of the parts 16 in the openings 13, the grate member 14 65 can be pushed inward against the fuel, so as to force it rearward, and then, when it is released, spaces will be provided between the grate member 14 and the fuel, so air can pass 70 up between the fuel and grate member 14, for aiding combustion of the fuel, and for protecting the grate member 14 against becoming overheated.

It will be seen that the grate member 14 is wider and of less height than the doorway 5, 75 so it can be passed through the doorway, and then turned to bring its parts 16 into position for lowering them into the openings 13; and when thus engaged with the grate member 11, it will be seen that the grate member 14 extends approximately to the side walls of the box 4, and its ends are adapted, to lean 80 against the sides or flanges 6, because of its width being greater than that of the doorway. A considerable space is provided between the 85 upper edge of the doorway and the upper edge of the grate member 14, and through this space, a poker can be thrust for shifting the upper part of the fuel, and besides, long pieces of wood can be passed through this opening, 90

(for making quick emergency fires) without disturbing the grate member 14. It will be seen that the upper part of the grate member 14 is considerably wider than its lower part, and this is necessary for providing an ample overlapping of the upper end of the grate on the flanges 6, especially in box stoves of which these flanges 6 are relatively narrow.

Even though the width of the grate member 11 is greater than the width of the doorway 5, and may be greater than the height of the doorway 5, nevertheless, it can be passed through the doorway while leaning it so that one edge will be adjacent to the right lower side, while the other edge will be adjacent to the left upper side, and when it has passed through the doorway, it can be turned horizontally, so its flanges rest upon the floor of the box 4.

Although I have described this embodiment of my invention specifically, it is not my intention to limit my patent protection to these exact details of construction and arrangement, for changes may be made within the scope of the inventive ideas as implied and claimed.

What I claim as my invention is:

1. In a grate for a box stove having a doorway that is wider at its middle part than at its lower end and having flanges extending inward at opposite sides of the doorway; the combination of a horizontal grate-member provided with supporting flanges at its opposite edges, said grate-member having openings therein at points near its front part but spaced a considerable distance from its front part, and an upright grate-member having depending legs provided with reduced lower ends that normally extend through said openings, and are loose therein, the upper parts of said legs being too wide to extend into said openings, so spaces are provided between them for receiving a poker for poking the fuel which is directly on the first said grate-member, the upper part of the said upright grate-member being wider than the lower part and providing a secure engagement with the said flanges of the doorway, said upright grate-member being normally inclined forward and adapted to lean against said flanges of the doorway, said upright grate-member being of less height than said doorway, so it can be passed through said doorway and placed into engagement with said openings of said horizontal grate-member.

2. The combination with a box stove that includes a doorway which is wider at its middle part than at its lower part and has flanges extending inward at opposite sides of the doorway; of a horizontal grate-member that is relatively long from front to rear and is adapted to be passed lengthwise through said doorway and is provided with flanges to support its main part at a distance above the floor of said stove, said grate-member having

openings in its front end portion but at a considerable distance inward from said doorway, and a forwardly leaning grate-member having legs extending through said openings while its upper end rests against the said flanges of the doorway, the said upright grate-member being of less height than said doorway and adapted to be passed therethrough and to have its legs engaged with said openings of the grate while the latter is seated in said stove.

In testimony whereof I affix my signature.
ELLA COX.
